John H. Bunninga,
His Attorney.

UNITED STATES PATENT OFFICE.

HARRY L. NOLAN, OF MAPLEWOOD, MISSOURI.

PUMP FOR OIL WELLS.

1,402,950.

Specification of Letters Patent. Patented Jan. 10, 1922.

Application filed February 16, 1920. Serial No. 359,206.

To all whom it may concern:

Be it known that I, HARRY L. NOLAN, a citizen of the United States, and residing at the city of Maplewood, county of St. Louis, Missouri, have invented the new and useful Improvement in Pumps for Oil Wells, of which the following is a specification.

This invention relates to pumps, and more particularly to deep well pumps employed especially in oil wells.

A pump of the character referred to, usually embodies a tubing or casing on the lower end of which is the working barrel, while the extreme end of the working barrel is provided with a perforated pipe or anchor. In the lower end of the working barrel is mounted a lower or standing valve, while reciprocating in this barrel is an upper or working valve forming a plunger attached to a sucker rod or wire cable, so that upon reciprocation, the liquid will be pumped up through the barrel and the tubing.

Now it is often necessary to remove and replace the standing valve or element and in the present practice, this requires the complete removal of the working element together with the sucker rods or cable, and the insertion of a rod bearing a gripping device, adapted to grip the standing element in order to permit withdrawal thereof from the casing. Now in replacement of a standing element, this requires first the complete removal of the working element with its sucker rods or cable; second, the insertion of a gripping element on this end of a rod or cable; third, the withdrawal of the gripping element with a standing valve; fourth, the insertion of a new standing valve and fifth, the replacement of the working valve with its sucker rods or cable.

One of the objects of this invention, therefore, is to provide a pump, whereby the removal or replacement of a standing valve may be accomplished with a minimum of labor and expense.

Another object is to provide a pump whereby the standing valve or element may be withdrawn by the working element or valve.

Another object is to provide a means for preventing injury to the standing and working elements during normal operation.

55 Further objects will appear from the de-

tail description taken in connection with the accompanying drawing, in which:

Figure 1 is a longitudinal vertical section through the working barrel and anchor of a deep well pump embodying this invention; 60

Figure 2 is a view similar to Figure 1, but showing the parts in different position; and,

Figures 3 and 4 are views similar to Figures 1 and 2, showing a further development 65 of this invention.

Referring to the accompanying drawing, and more particularly to Figs. 1 and 2, 1 designates the working barrel, which is connected by a suitable coupling (not shown) 70 with the tubing or casing (not shown) of the well. The lower end of the barrel is connected by a coupling 2 with a perforated pipe or anchor 3, the inside surface 4 of the coupling 2 being of slightly smaller diameter than the inside of the working barrel. 75

Mounted in the bottom of the barrel is the lower or standing valve or element 5, which has a leather or other suitable face 6 cooperating with the surface 4 and has further a ball valve 7 arranged in a cage portion 8 of the standing element, which cage portion terminates in a boss 9 provided with a perforation and also preferably threaded internally. 80

Mounted in the barrel and on the end of the sucker rod 10 (or wire cable) is a working valve or element 11 which is also provided with a cage 12 and a ball 13. The working valve is provided with a series of 90 washers 14, of leather or any other suitable material, so as to provide a plunger. The lower end of the working valve has threaded thereon a head 15 which may be provided with a loop 16 or with a perforated cup as 95 is usual in these pumps.

The parts so far described are of any suitable and usual construction, and a detail description thereof is, therefore, unnecessary; suffice it to say that the working valve during its reciprocation cooperates with the standing valve to cause an upward flow of the liquid in the working barrel and the tubing or casing. The distance between the lower end of the working valve and the 100 standing valve is, however, even in the lower limit of movement of the working valve, not over six inches; accordingly, during the normal operation, the working valve will 105 not approach closely to the standing valve. 110

As heretofore described, it is often necessary to remove and replace the standing valve. In accordance with this invention, therefore, the bottom of the working valve 5 or element is provided with a tap 17. This tap can be secured to the head 15 in any suitable manner, as by welding, riveting, or a threaded connection, properly locked, or it may even form an integral part thereof. 10 This tap is constructed of steel, carefully hardened and tempered, and is a tapered tap such as is used to cut pipe threads. The tap is provided with a starting point 30 at its end, and is a cutting tap as distinguished 15 from an ordinary fluted screw; the provision of the starting point at the extreme tip enables the tap to readily enter and be guided into the perforations as hereinafter described. The tap is arranged centrally so 20 as to cooperate with the perforation in the boss 9.

The operation and function of this construction is as follows: During the normal operation of the pump, the tap on the end 25 of the working element will not engage the standing element. When, however, it is desired to remove the standing element, the working element is dropped until the tap engages the perforation in the boss 9. The 30 provision of the starting point 30 allows this point to enter the perforation on the boss 9 so that the tap will be clearly correctly positioned to begin cutting. Then the working element is turned by turning 35 of the sucker rod or cable, causing the tap to cut into the standing element and thus obtain a firm grip. By then raising on the sucker rod or cable, the standing element can be withdrawn. The standing element 40 can be replaced in a similar way, or dropped in place.

Referring now to Figures 3 and 4, in which like parts are designated by the same reference characters as in Figures 1 and 2, 45 the tap 17 has its shank threaded as shown at 20, and on this tap and shank is threaded an interiorly threaded sleeve 21 provided with a clutch face 22 adapted to cooperate with a corresponding clutch face 23 on the 50 perforated boss 9. The sleeve 21 is retained in normal position, with its clutch face 22 projecting slightly beyond the point of the tap, by a soft iron pin 24 passing through the sleeve and the tap, this pin being secured in any suitable manner as by being driven in place or by having its ends riveted. 55

During the normal operation of the working element the sleeve 21 is retained in a position as shown in Figure 3 so as to cover 60 the tap. Accordingly, if the working element should be dropped accidentally, the sleeve will act as a bumper so as to prevent injury to the tap or standing element. When, however, it is desired to remove the standing 65 element, the working element, with its at-

tached tap and sleeve, is dropped, thereby causing the clutch face 22 to contact with the clutch face 23. If now, the working element is turned by turning of the sucker rod, the clutch faces 22 and 23 are interlocked, 70 thereby preventing the sleeve 21 from turning. The soft metal pin 24 is now sheared off, and upon further turning of the working element, the tap will screw through the sleeve and into the threaded boss 9 so as to 75 cut itself therein and firmly grip the standing element. During this cutting movement, the sleeve 21 acts as a guide so as to direct the tap and the standing element, and brace the same during its cutting movement therein. 80 The standing element can now be withdrawn from the pump.

It will, therefore, be seen that the invention accomplishes its objects. The removal and replacement of the standing valve is 85 accomplished without requiring entire dismantling of the entire pump and without requiring the series of operations referred to above as is the case with the prior art. It is important that the gripping element be 90 a tap, for an ordinary threaded boss will not accomplish the purpose, for the reason that the presence of sand and grit found in wells, and oil and grease will so interfere with the proper gripping of threads as to 95 render the mere provision of a cooperating boss and a tapped hole inoperative for the purpose of withdrawing the standing element from the well. A tap, however, definitely cuts its way into the standing element 100 and accordingly, it is absolutely sure and certain in its action, no matter what may be the condition as to foreign matter and corrosion at the bottom of the well.

The provision of the combined bumper 105 and guiding element for the tap not only prevents injury to the tap and not only accurately centers, guides and braces the tap while cutting into the standing element, but it also serves to cover the tap during the 110 normal operation and thus prevents injury to the tap. Accordingly, the tap is always in condition for use with its edges sharp and clean.

It is obvious that various changes may be 115 made in the details of construction without departing from the spirit of this invention; it is, therefore, to be understood that this invention is not to be limited to the specific details shown and described.

Having thus described the invention, what is claimed is:

1. A pump embodying a barrel, a standing element and a working element therein, characterized by the feature that one of the elements has a cutting tap provided with a starting point and the other element has a cooperating perforation, said starting point being adapted to enter said perforation and permit the tap to start and to cut therein 130

and grip the perforated part, whereby the standing element may be withdrawn by the working element through the medium of the tap.

5 2. A pump embodying a barrel, a standing element and a working element therein, characterized by a tap on one of said ele-

ments adapted to make connection with the other element, and a sleeve threaded on said tap and normally retained against rotation thereon.

In testimony whereof I affix my signature this 7th day of January, 1920.

HARRY L. NOLAN.
